(57) **CLAIM**

The ornamental design for a yard stake, as shown and described.

DESCRIPTION

FIG. 1 is a front perspective view of a yard stake according to an exemplary embodiment of the present invention;

FIG. 2 is a rear perspective view of the yard stake of FIG. 1;

FIG. 3 is a front elevational view of the yard stake of FIG. 1;

FIG. 4 is a rear elevational view of the yard stake of FIG. 1;

FIG. 5 is a left side elevational view of the yard stake of FIG. 1, with the right side elevational view of the yard stake being identical;

FIG. 6 is a top plan view of the yard stake of FIG. 1; and,

FIG. 7 is a bottom plan view of the yard stake of FIG. 1.

1 Claim, 3 Drawing Sheets
